CHRISTIAN F. LAUN, OF WATERVILLE, CONNECTICUT, ASSIGNOR TO BERBECKER & ROWLAND MANUFACTURING COMPANY, OF WATERVILLE, CONNECTICUT, A CORPORATION OF CONNECTICUT.

CURTAIN-ROD AND BRACKET.

1,127,459.

Specification of Letters Patent.

Patented Feb. 9, 1915.

Application filed September 12, 1914. Serial No. 861,350.

To all whom it may concern:

Be it known that I, CHRISTIAN F. LAUN, a citizen of the United States, and a resident of Waterville, in the county of New Haven 5 and State of Connecticut, have made and invented certain new and useful Improvements in Curtain-Rods and Brackets, of which the following is a specification.

My invention relates to an improvement 10 in curtain rods and brackets for supporting the ends of the same, the object being to provide a rod the ends of which may be easily and readily engaged and disengaged from the supporting bracket and the latter to be 15 so constructed that they may be manufactured at a small cost, readily secured in place, and though preferably stamped from a single piece of metal, yet be sufficiently strong to withstand any strain likely to be 20 imposed thereon.

A further object of the invention is to impart a neat, attractive and finished appearance to both the pole and brackets, and with these and other ends in view the invention 25 consists in certain novel features of construction and combinations of parts as will be hereinafter fully described and pointed out in the claims.

In the accompanying drawings, Figure 1 30 is a top plan view of my improved pole and bracket in their assembled positions. Fig. 2 is an enlarged view in side elevation of one end of the pole supported in the bracket. Fig. 3 is a similar view, partly in section and 35 partly in side elevation. Fig. 4 is a sectional view taken on the line 4-4 of Fig. 2 and looking in the direction as indicated by the arrow. Fig. 5 is a detached face view of one of the supporting brackets. Fig. 6 40 is a perspective view of the same. Fig. 7 is a face view of a modified form of the bracket secured to the window casing or other support. Fig. 8 is a plan view of a modified form of one pole end and bracket. 45 Figs. 9 and 10 are vertical sectional views of other modified forms thereof. Fig. 11 is a view of one pole end and bracket showing modified means for preventing the pole from becoming disengaged from the bracket lengthwise thereof. Fig. 12 is a detached 50 view showing the bracket secured to the support by two retaining screws.

Referring to the drawings, it will be seen that the rod is of the telescopic or extension

type, that is, the one bracket 10 telescopes or 55 fits within the bracket 11 in order that it may be extended or shortened to adapt it to fit windows, doors, or other openings of varying width. The ends of this extension rod are bent or curved into what are generally 60 known and referred to as "goose-necks", that is, curved at right angles to the remaining portion thereof, the ends being enlarged as illustrated at 12, these enlarged ends being preferably made of separate pieces 65 and soldered or otherwise secured to the rod 10-11. In the preferred form, these ends 12 are provided with a rib or flange 13 extending wholly or partially around the same, and either stamped or struck up from 70 the metal of which the ends 12 are made, or in the form of separate rings secured thereto. In each extreme end of the rod is formed an opening or socket 14 into which projects a portion of the bracket, as herein- 75 after explained.

The bracket, as clearly illustrated in section in Fig. 3, is preferably stamped out of a single continuous piece of metal, the one portion 15, that is, that part which fits or 80 rests against, and secured thereto, the casing or other support 21, being bent at right angles to the part 16 which supports the pole end. The vertical attaching plate 15 has its extreme vertical edges slightly bent 85 or turned up in order to lend additional strength to the plate, and also add to the finished and neat appearance thereof. This plate 15 is also provided with a hole or perforation 18 (Fig. 5) for the passage of the 90 retaining screw 19, a raised wall, flange or rib 20 encircling the upper edge of this hole, but not the lower, so that when the bracket is secured to the support 21, a part of the screw head 22 rests or impinges against the 95 offset 20, leaving a space or recess 23 between the remaining portion of the screw head and the plate 15 where said offset or rib is omitted or broken away.

Below the flanged opening 18, the plate 100 15 is provided with a boss 24, preferably dome-shape, or in the form of a sector of a sphere, the diameter thereof being such that it will project into the hole or socket 14 formed in the extreme free end of the rod 105 and assist in centering the latter in the bracket. Instead, however, of this centering lug or boss being made integral with

the plate 15, it may be made separate therefrom, as, for instance, a second retaining screw 25 may be used as illustrated in Fig. 7, the screw head being of such diameter as 5 to be nicely contained within the hole or socket 14 formed in the pole end, and to operate to center the end as in the case of the boss illustrated in section in Fig. 3. Again, as illustrated in Fig. 12, the plate 29 may be 10 so formed as to receive two retaining screws 26, 27, instead of one as heretofore suggested, a boss 28 being also employed as in the instance illustrated in Fig. 3, the two screws 26, 27, overcoming any liability of the 15 bracket swinging or tilting with respect to its support.

The supporting plate 16 of the bracket, as before described, is made integral with the attaching plate 15 and extends at right 20 angles thereto, this plate being curved in cross-section to conform to the curvature of the pole end adapted to rest therein, this plate, if desired, being constructed with the stamped up ribs 30, 31, as illustrated in Fig. 25 4 for the purpose of strengthening the same. In its preferred form, this curved plate is cut away at its rear end, as illustrated at 32, Fig. 2, the free or forward end 33 encircling approximately one-half of the pole end 12. 30 This portion of the plate is also provided with a recess 34, which, when the end 12 is inserted in position within the bracket, receives and retains the rib or flange 13, these means assisting in preventing the rod from 35 becoming detached from the bracket in the direction of the length of said rod. If desired, however, this recess may be formed in the pole end as illustrated at 35, Fig. 11, and the circular rib or flange formed on the 40 plate 16, as illustrated at 36, Fig. 11. Again, in order to effect a partial locking of the pole end and bracket, the rib and recess above referred to may be omitted and other means substituted therefor, such, for instance, as illustrated in Fig. 8, wherein the 45 rod 37 is shown with an enlarged end 38, the latter providing a shoulder at the junction of the two parts. In this instance, the outer extreme edge 39 of the horizontal sup- 50 porting plate 40 of the bracket will be upturned in order to engage the said shoulder, thus preventing the rod end from becoming accidentally disengaged from the plate.

In assembling the rod with the brackets, 55 the former is slightly tilted, so that the socket or opening 14 in the ends of the rod will receive a boss or projection 24, and so that the upper edge of the extreme end of the rod will fit under the head 22 of the retaining screw 19. The ends of the rod are then lowered onto the supporting plates of the bracket, whereupon the lower edge of the screw head will fit into a groove or recess 41 formed in the end 12 as clearly illustrated in Figs. 2 and 3 of the drawing, the

upper edge of the extreme end fitting in the recess 23, that is, between the lower portion of the screw head and the vertical plate 15. When thus assembled, it will be understood that the ends of the rod are held or supported in the curved plates 16 of the brackets, the rib 13 on the end of the rod fitting in the recess 34 of the supporting plate of the bracket, the boss 24 into the extreme end of the rod, and the edge of the free ends of the rod fitting between the screw head and vertical plate of the bracket, these means insuring against any accidental disengagement of the rod from the brackets. Instead, however, of providing a recess between the screw head 22 and the rear plate by means of the wall or offset 20, the latter may be omitted as illustrated in Fig. 9, the screw head 42 projecting sufficiently far out from the vertical plate 43 of the bracket to provide such a recess 44. Or, if desired, the screw may be formed with a hub 45 as illustrated in Fig. 10, which, when the screw is driven home, impinges against the vertical plate 46, providing the necessary recess 47. In all of these instances, however, the lower edge of the screw head will fit into the groove or recess 41 formed in the pole end and thus operate to not only prevent the pole end from being drawn out from the bracket in a longitudinal direction, but also in a vertical direction, the screw head also acting as a fulcrum for the end of the rod when the latter is lowered into place into the curved horizontal plates 16 of the bracket.

What I claim is:—

1. A curtain rod bracket comprising an attaching plate provided with an opening partially surrounded by an offset for the passage of a retaining screw, said offset adapted to receive the head of a screw thereagainst and maintain the same spaced a distance from the said attaching plate, a rod supporting plate carried by said attaching plate adapted to receive a rod therein and to maintain the same against the unsupported portion of said screw head.

2. A curtain rod bracket comprising an attaching plate provided with an opening partially surrounded by an offset for the passage of a retaining screw, and adapted to hold the head thereof spaced from said attaching plate and a rod receiving plate curved in cross-section projecting from and supported by the said attaching plate, said supporting plate provided with means adapted to engage and resiliently retain a rod therein.

3. A curtain rod bracket comprising a vertical plate provided with an opening partially surrounded by an offset for the passage of a retaining screw, the said offset adapted to receive the head of a screw thereagainst and hold the same spaced a distance

from the said vertical plate, and a horizontal plate curved in cross-section to receive and support the end of the rod.

4. A curtain rod bracket comprising a vertical plate having an opening partially surrounded by an offset for the passage of a retaining screw, the said offset adapted to retain the head of said retaining screw spaced a distance from the said vertical plate and with means for centering the end of a curtain rod, and a horizontal plate curved in cross-section for receiving and retaining the end of said curtain rod.

5. A curtain rod bracket formed from a single piece of metal and comprising a vertical plate provided with an opening partially surrounded by an offset for the passage of a retaining screw, said offset adapted to receive the head of the retaining screw thereagainst, and to hold the same in spaced relation, with respect to said vertical plate, and with means for centering the end of a curtain rod, and a horizontal plate curved in cross-section for receiving and retaining the end of said curtain rod.

6. A curtain rod bracket formed from a single continuous piece of metal and comprising a vertical plate the vertical edges of which are bent at substantially right angles to said plate, said plate being provided with an opening partially surrounded by an offset for the passage of a retaining screw, said offset adapted to receive the head of the retaining screw thereagainst, and to hold the same spaced a distance from said vertical plate and with a projection below said opening, and a horizontal plate curved in cross-section for receiving and supporting the end of a curtain rod.

7. A curtain rod bracket comprising vertical and horizontal plates, said vertical plate being provided with an opening, said horizontal plate being curved in cross-section, a retaining screw passing through the opening in said vertical plate, the head of which screw projects out beyond said plate, and a curtain rod supported on said horizontal plate and the end of which engages the head of said screw passing through said vertical plate.

8. A curtain rod bracket comprising ver-

tical and horizontal plates, the said vertical plate being provided with an opening, a retaining screw passing through said opening and having its head projecting out beyond said vertical plate, a curtain rod supported on said horizontal plate and having its head engaging the projecting head of said screw, and means provided on said curtain rod and bracket whereby to prevent the accidental disengagement of the same.

9. A curtain rod bracket comprising vertical and horizontal plates, said vertical plate being provided with an opening partially surrounded by an offset, a screw passing through said opening and having its head resting upon said offset, a curtain rod the end of which is supported on said horizontal plate, the extreme end thereof engaging with the head of said screw.

10. A curtain rod bracket comprising vertical and horizontal plates, said vertical plate being provided with an opening and below it a projection, a retaining screw passing through said opening in the vertical plate and having its head projecting out beyond the latter, a curtain rod supported on said horizontal plate and in the end of which fits said projection on the vertical plate, the end of said rod engaging the head of said retaining screw.

11. A curtain rod bracket comprising an attaching plate provided with an opening, a retaining screw passing through said opening, and means disposed between said attaching plate and the head of said screw, holding the latter out beyond said plate, said attaching plate provided with a projection adapted to receive and center the end of a rod which fits thereagainst, and a rod supporting plate carried by and projecting from said attaching plate and adapted to receive and support a rod therein.

Signed at Waterville, in the county of New Haven and State of Connecticut, this 9th day of September, A. D. 1914.
